UNITED STATES PATENT OFFICE.

FRANK HIRTH, OF FORT SMITH, ARKANSAS.

REFRIGERATING APPARATUS.

1,100,015.

Specification of Letters Patent. Patented June 16, 1914.

Application filed August 29, 1913. Serial No. 787,291.

To all whom it may concern:

Be it known that I, FRANK HIRTH, a citizen of the United States, residing in Fort Smith, in the county of Sebastian and State of Arkansas, have invented certain new and useful Improvements in Refrigerating Apparatus, of which the following is a specification.

This invention relates particularly to refrigerating systems and ice-making apparatus of the kind in which gaseous ammonia is compressed, passed through a condenser, where it is liquefied, transferred in a liquid form to a receiver, then carried to freezing tanks or other means for freezing or refrigerating and thence reconveyed to the compressor and carried again to the condensers, but the invention may be employed in other systems or apparatus varying in detail from that above outlined.

In apparatus of the class above specified, the liquid ammonia is often mixed or contaminated with uncondensed foul gases which clog the apparatus and impair its efficiency, often requiring an unnecessarily high pressure to effect the circulation of the fluids or a stoppage of the apparatus until the foul gases are eliminated. It has been found in practice that such foul gases would not only partly fill the condenser but would pass with the liquid ammonia to the receiver and thence to the freezing tanks being trapped therein, impairing the efficiency thereof and preventing a proper circulation of the refrigerating medium. Heretofore it has been necessary to suspend the operation of the apparatus until the foul gases were allowed to escape or were blown off, or to work under high pressure with increased cost of operation and with reduced efficiency.

The object of this invention is to remove such uncondensed foul gases from the system and to thus increase the efficiency of the apparatus under a comparatively low pressure and without shutting down the plant.

In carrying out my invention I connect the condenser with a liquid receiver in the usual way and I provide a receiver for foul gases which is also connected with the condenser and has a separate connection with the liquid receiver. The foul gas receiver is located above the liquid receiver and above the condenser and is provided with means for cooling it in such manner that any ammonia which may pass to the foul gas receiver is condensed and passes to the liquid

receiver, while the foul gases are allowed to escape through a suitable outlet.

The accompanying drawing shows diagrammatically so much of a refrigerating apparatus with my invention applied as is necessary to illustrate my improvements.

The condenser A may be of the usual kind and receives ammonia from the compressors in the usual way. The liquid receiver B may also in general be of usual construction and it is connected with the condenser A by a pipe line C joined by a T-coupling c to a valve D in turn connected with a valve E joined to the condenser. The pipe C is provided with a suitable valve C'.

The foul gas receiver F is in the form of a closed cylinder slightly inclined and joined by a pipe G with the coupling c and thus connected with the condenser. The pipe G is provided with a valve g to open and close communication between the condenser and the foul gas receiver and the upper end of the foul gas receiver is provided with a valved outlet H for foul gases. The receiver F is held in an inclined position by suitable supports or standards f and the lower end of the receiver is connected by a pipe I with the liquid receiver B and this pipe I is provided with a suitable valve J.

K indicates a perforated pipe for spraying water onto the receiver F thus cooling it and causing any gaseous ammonia which may be in the receiver to be condensed.

L indicates a gage of any suitable construction applied to the receiver F.

The liquid receiver B is connected at M in any suitable way with the freezing tanks or other desired parts of the refrigerating apparatus.

P indicates a gage of suitable construction applied to the receiver B, and N and O indicate valved pipes usually employed in this class of apparatus, N being a blow-off pipe and O being connected with the condenser, as usual.

In the normal operation of the apparatus the valves g and J are closed and the valves D, E and C' are also closed. The liquid ammonia passes from the condenser to the receiver by way of the pipe O in the usual way and is conveyed from the receiver according to the usual practice. If foul gas is indicated, or is present, the valves E, D, g, C' and J are opened. Any foul gases which may rise to the coupling c with the liquid ammonia separate from the liquid and pass

to the foul gas receiver F through the pipe G and may be allowed to escape through the outlet H which may be left open or may be opened from time to time. Usually the foul gases are mixed with gaseous ammonia and in order to save this the spray pipe K is employed which condenses the gaseous ammonia which will collect on the bottom of the inclined receiver and pass, by way of the pipe I, to the liquid receiver B, while the uncondensable gases remain in the upper part of the receiver F or pass out through the outlet H. The liquid level in the receiver F is indicated by the gage L. The pipe C acts as an equalizing pipe line when the valves g and J are opened.

Practice has shown that by my improvements the efficiency of the apparatus is greatly increased,—a comparatively low temperature only is required, there is less consumption of fuel and the expense of operation is greatly reduced.

I claim as my invention:—

1. A refrigerating apparatus, comprising a condenser, a receiver for the liquid ammonia, a foul gas receiver located above and connected with the upper part of the condenser, a connection between the lower part of the condenser and the liquid ammonia receiver, and a connection between said foul gas receiver and the receiver for liquid ammonia.

2. A refrigerating apparatus, comprising a condenser, a receiver for the liquid ammonia, a foul gas receiver located above and connected with the upper part of the condenser, means for cooling said foul gas receiver, a connection between the lower part

of the condenser and the receiver for liquid ammonia, and a connection between said foul gas receiver and the receiver for the liquid ammonia.

3. A refrigerating apparatus, comprising a condenser, a receiver for the liquid ammonia, a pipe line (C) connected with the receiver for liquid ammonia and with the upper part of the condenser, a foul gas receiver located above the liquid receiver and connected with said pipe line (C), and a connection between the foul gas receiver and the receiver for liquid ammonia.

4. A refrigerating apparatus, comprising a condenser, a receiver for the liquid ammonia, a connection between the condenser and said receiver, a foul gas receiver disposed at an inclination having its lower end connected with the condenser and its upper end provided with a valved outlet, and a connection between the foul gas receiver and the liquid receiver.

5. A refrigerating apparatus, comprising a condenser, a receiver for the liquid ammonia connected therewith, a foul gas receiver disposed on an incline, having its lower end connected with the condenser and its upper end provided with a valved outlet, means for cooling the foul gas receiver and a connection between the lower end of said foul gas receiver and the receiver for liquid ammonia.

In testimony whereof, I have hereunto subscribed my name.

FRANK HIRTH.
